UNITED STATES PATENT OFFICE.

GEORGE A. FINSTER, OF SCHENECTADY, NEW YORK.

CARTRIDGE.

No. 878,369.

Specification of Letters Patent.

Patented Feb. 4, 1908.

Application filed August 16, 1907. Serial No. 388,912.

To all whom it may concern:

Be it known that I, GEORGE A. FINSTER, a citizen of the United States, residing at Schenectady, in the county of Schenectady and State of New York, have invented certain new and useful Improvements in Cartridges; and I do declare the following to be a full, clear, and exact description of the invention, such as will enable others skilled in the art to which it appertains to make and use the same.

This invention relates to an improved explosive, which may be used in either large or small projectiles.

15 The object of the invention is to provide a cheap explosive for use in projectiles of various sizes which will not explode until coming in violent contact with an object.

20 In the accompanying drawings,— Figure 1 represents a longitudinal section of a cartridge constructed in accordance with this invention; Fig. 2 represents a transverse section of a cartridge showing a slightly modified form of the invention; Fig. 3 represents a similar view of another modification.

25 In the embodiment illustrated in Fig. 1 a cartridge is shown comprising a shell 1, preferably of steel coated with shellac to prevent rusting thereof, and having a frangible partition 2, preferably of glass, arranged transversely thereof and connected therewith by putty 3 or in any other suitable manner, whereby it may be liquid-tight. This frangible partition divides the shell into two compartments 4 and 5. The compartment 5 is filled with metallic sodium, preferably having a small amount of kerosene oil mixed therewith to prevent the sodium from melting in hot climates.

30 The two members may be connected by putty or cement 3, or in any other suitable manner.

The compartment 4 is filled with water or other suitable liquid which coming in contact with the sodium will cause it to explode with great violence.

In the form shown in Fig. 2 a glass parti-

tion 6 is shown arranged longitudinally of the cartridge with the water and sodium compartments arranged on opposite sides 50 thereof.

In Fig. 3 is shown a hollow ball composed of two members 7 and 8 separably connected, the member 7 having an annular internally screw-threaded flange 9 adapted to engage 55 an externally screw-threaded flange 10 formed on the member 8. The member 7 has a covering 11 of glass or other frangible material arranged across the face which is adapted to be connected with the other 60 member, and the compartment so formed is filled with water. The other member 8 is filled with metallic sodium and operates in the same manner as the above described form.

65 In the use of this invention when the projectile comes in contact with a ship or other object the glass partition is broken and the water mixes with the metallic sodium, thereby causing a terrific explosion, damaging 70 and injuring everything adjacent thereto.

I claim as my invention:—

1. An explosive projectile composed of two separably connected members having a frangible partition arranged between them 75 at the point of connection, one member containing an explosive compound and the other means for exploding said compound when coming in contact therewith.

2. An explosive projectile composed of 80 two separably connected members, one of which has an internally screw-threaded flange provided on its meeting face and the other an externally screw-threaded flange for co-operation with the flange on the other 85 member, and a frangible partition arranged between the meeting ends of said members.

In testimony whereof I have hereunto set my hand in presence of two subscribing witnesses.

GEORGE A. FINSTER.
